CLOSURE ARRANGEMENT FOR THE PLANISHING OPENING OF HORIZONTAL COKE OVEN CHAMBERS

Ernst Wolff, Bochum-Linden, Germany

Application August 1, 1951, Serial No. 239,718

Claims priority, application Germany August 2, 1950

3 Claims. (Cl. 202—248)

The present invention relates to closures for the planishing opening of horizontal coke oven chambers which are charged with loose coal from the top. When charging coal it is known that below the individual charging openings there form cone shaped piles which have to be leveled by means of a planishing rod operated by a machine. If not the obsolete clay sealing operation was used, the closures for the planishing opening of the above-mentioned ovens were sealed by ordinary asbestos gaskets or by iron on iron; in the last-mentioned instance the surfaces contacting each other were machined.

Both types of sealing the planishing opening are deficient. The asbestos became hard after a relatively short time. Also the life of asbestos is rather limited. Therefore, asbestos sealings are seldom used nowadays.

A perfect sealing between two iron surfaces fails for the reason that the contacting areas do not contact each other at all points thereof, although, as mentioned, they may be machined and may be pressed against each other by a latch. Each planishing door warps and dislocates because its portions are unevenly heated and therefore expand unevenly. Those portions facing the interior of the oven expand more than those portions remote from the oven. For this reason there will be observed with planishing doors which usually are rectangularly shaped, that they are bent back at the top and at the bottom. Through the lower gap, tar condensates which, as is known condensates on the planishing door during the coking process, will escape toward the outside, will soil the oven door and will make the operation more difficult. Through the upper gap, depending on the value of the differential pressures, air will enter into the oven chamber or coking gases will escape toward the outside.

It is, therefore, an object of this invention to provide a closure for the planishing opening of a horizontal coke oven chamber which will overcome the above-mentioned drawbacks.

It is a further object of this invention to provide a closure arrangement for a horizontal coke oven chamber which will be self-sealing.

Still another object of this invention consists in the provision of a closure arrangement of the type set forth above which will prevent any material accumulation of tar condensate at the closure body, especially at the inside of the door for the planishing opening.

It is still another object of this invention to provide a planishing door for the planishing opening of horizontal coke oven chambers in which the door for the planishing opening is movable parallel to the frame of said opening.

It is also an object of this invention to provide a planishing door of the type referred to in the preceding paragraphs with a fire screen which will prevent the transfer of any excessive heat to the planishing door so that the latter will be free from stresses which otherwise may be caused by the heat in the oven.

These and other objects and advantages of the invention will appear more clearly from the following specifica-

2

cation in connection with the accompanying drawings in which:

Figure 1 illustrates a view of a planishing door according to a first embodiment of the present invention.

5 Figure 2 represents a section along the line II—II of Figure 1.

Figure 3 is a section along the line III—III of Figure 1.

Figure 4 shows a portion of Figure 2, however at a larger scale than the latter.

10 Figure 5 represents a planishing door according to a second embodiment of the present invention.

Figure 6 illustrates a section along the line VI—VI of Figure 5.

15 Figure 7 is a section along the line VII—VII of Figure 5.

Figure 8 represents a portion of Figure 7, however on a larger scale than shown in the latter.

Figure 9 is a section through a closure arrangement of still another embodiment of the present invention.

20 Fig. 10 is a view of another embodiment of a planishing door according to the invention.

Fig. 11 is a section along the line 11—11 of Fig. 10.

General arrangement

25 The principle of the invention consists primarily in that the planishing closure is provided with a metallic self-sealing arrangement in such a manner that a first sealing means provided at the closure member and a second sealing means provided at the door frame contact

30 each other when the closure member is in its closing position, at least one of said sealing means being yieldable and preferably adjustable. Such yieldable and adjustable self-sealing may for instance be obtained by providing a sealing ledge on the closure member which sealing ledge extends over the entire circumference of said closure member. This sealing ledge tightly embraces the closure member and is maintained in its position relative to said closure member by frictional pressure. When the closure member is in its closing position, the sealing ledge abuts a

35 corresponding sealing surface of the door frame. Warping of the closure member may easily be compensated by driving the sealing ledge forward by means of hammer blows in such a manner that the sealing ledge extending all around and being shaped as a sharp edge contacts the counter surface at all points. The yieldable and adjustable sealing ledge proper practically does not suffer any temperature stresses because only a small projection of its surface is subjected to heat influence and the shape of its cross section compensates differences in temperature.

40 50 The contact of material with metal alone, with the sealing arrangement according to the present invention, does, however, not accomplish a complete gas tight sealing. Such gas tight sealing is obtained only by the fact that the oven gases cool off at the sealing edge, as a result of which tar deposits which latter so to speak seals the sealing surface.

55 The tar condensates depositing at the door surface itself flow downwardly on the inner side of the door body and collect above the lower sealing edge. When the door is now opened, it sometimes happens that larger quantities of tar condensates flow toward the outside.

60 In order to avoid the last-mentioned drawback, according to a further feature of the present invention, the sealing edge at the lower portion of the door, especially at the lower smaller side of the rectangle forming the door opening, is discarded and is replaced by a wide sealing strip which protrudes beyond the inner edge of the door frame. Due to the larger quantities of condensates which are always present at this portion of the door frame, a linear contact area as is otherwise required between the sealing edge and the door frame, is not necessary at this portion, rather a contact surface may be made.

use of here. The sealing strip just mentioned is preferably shaped so that it will slope with its upper edge toward the opening of the oven.

The application of the sealing arrangement according to the present invention is based on the provision that the door body may be moved parallel to itself, since otherwise it is difficult, after the door has been closed and latched, to cause the sealing surfaces of the door and of the frame evenly to contact each other at all sides. With those doors with which the door body is inserted and removed as an entirety, the above-mentioned parallel movement is already present. However, a special removing mechanism is required. In order to make it possible to use the sealing arrangement according to the present invention also with ordinary doors hinged to the frame of the planishing opening, there is according to the present invention provided a mechanism which makes it possible to move such hinged door parallel to itself so that the door may be latched in the same manner as removable doors. To this end, there is provided a latch which in the closing position of the oven door hinged to the door frame catches behind hooks arranged at the door frame in such a manner that by means of inclined surfaces on the hooks and by oval shaped bores in the hinges of the door body a parallel movement of the door body toward the door frame is effected. The said latch is in a manner known per se tiltably mounted on the door body. In order to relieve the door hinge and to enable the condensate flowing down the door to return to the oven chamber, it is advantageous to provide at the door body a horizontal foot ledge which in the closing position of the door rests on a horizontal supporting surface of the frame. That hook which is remote from that side of the door at which the hinges are located, is preferably rigidly connected to the door frame. The other hook, however, may advantageously be rigidly connected with the rotatable hinge bolt which latter by means of a coupling pin or the like takes part at the turning movement of the door body. With this arrangement, the door opening can be completely laid open while the hook adjacent the hinges will not be obstructive in any way. In some instances there might not be sufficient space to allow the hook connected to the hinge bolt fully to swing open. In order nevertheless to make it possible to open the door body to a desired degree, the coupling pin may be arranged in a cut-out portion of the hinge eye of the door body in such a manner that it is taken along only after the door has been opened by a predetermined angle.

In order especially to protect the movable parts of the door from the oven heat, it is known at the inner side of the door body to provide a fire screen. A further development of the present invention concerns a special arrangement of such a fire screen for cooperation with and protection of the planishing door. To this end the fire screen is arranged so that it can easily be exchanged by lifting the same upwardly while being mounted in a dovetail guiding arrangement of the door body. In this way, the fire screen can easily yield to the heat stresses which may occur, without conveying these stresses to the door body.

Structural arrangement.

Referring now to the drawings in detail and Figures 1 to 4 thereof in particular, the structure shown therein comprises the closure body 1 which is provided at the outside thereof with a flange 2 extending all around. Mounted on the flange 2 at even distances there are threaded hooks 3. These threaded hooks yieldably hold a sealing ledge 4 and clamp the same against an adjacent surface of the closure body 1. As will be clear from the drawing, the said sealing ledge 4 consists of a plurality of strips. At the lower part of the flange 2 there is provided a wide sealing strip 5 which is likewise held by threaded hooks 3. The sealing strip 5 protrudes beyond the upper edge of the closure frame 6 and is inclined to-

wards the latter. The condensates forming on the area surrounded by the sealing, flow downwardly on the inclined surface of the sealing strip 5 and thus return into the oven chamber. The closure body 1 is threaded 5 engaged by a bolt 31 which latter carries the closure lever or latch 32 and is provided with a square head 33. In order to close the planishing opening, the planishing closure is lifted by a lifting device which latter engages the closure at the ear 34 and places the closure from above in front of the planishing opening in such a manner that the closure latch 32 properly catches behind the hooks 35 connected to the closure frame 6. If now the bolt 31 by actuating the square-head 33 is turned so that it moves in a direction out of the closure body 1, the bolt will move the closure member 1 parallel to itself against the closure frame 6, thereby tightly pressing the sealing edge 4 and the sealing strip 5 against the sealing surface 7 extending all the way around the closure frame 6. Inasmuch as the sealing edge 4 and the sealing strip 5 are yieldably supported by the clamping effect, they are able to adapt themselves to any unevenness of the sealing surface 7 which may have been brought about by warping. In order to compensate such unevenness, it is generally sufficient to deal a few strong hammer blows to the outer edge of the sealing ledge or the sealing strip respectively. If desired, the clamping effect exerted by the threaded hooks 3 may be reduced by correspondingly loosening the screw nuts 8 to the desired extent. The upper edge 9 of the closure frame 6 is provided with a sloping surface 30 at the lower small side, which sloping surface slopes downwardly from the outer edge portion toward the oven chamber. This arrangement will facilitate the return of the formed condensates into the chamber.

Referring now to the embodiment shown in Figures 5 to 8, the door frame 10 is in a manner similar to the arrangement shown in Figures 1 to 4 inserted into the masonry of the oven and is provided on the outside thereof with a sealing surface 11 extending all the way around. Also with this embodiment a sealing edge 4 and a sealing strip 5 are connected to the door body 12 by means of threaded screws 3. A hinge bolt 14 is journaled in the hinge eyes 13 of the door frame 10. The hinge eyes 13 of the door body 12 are provided with oval bores 16 and surround or grip around the hinge bolt 14. The upper hinge eye of the door body is provided with a sector shaped cut-out 17 which is engaged by a coupling pin 18 rigidly connected to the hinge bolt 14. Between the hinge eyes 13 of the frame, the bolt 14 is provided with a slideable but not rotatably arranged sleeve 19. Rigidly connected to the sleeve 19 is a hook 20 with its loop directed upwardly. One the other side of the door frame and connected therewith is another hook 21 the loop of which is directed downwardly. Each of the two hooks is provided at the inner side thereof with a slant area 22. A latch 23 is tiltably mounted on the door body 12 and is journaled on a square head bolt 24. This latch is arranged so that in the closing position of the door it will catch behind the hooks 20 and 21. The door body 12 is provided on the inner side thereof with a protruding part 25 forming a dovetail shaped guide. The fire screen 26 arranged somewhat more inwardly is provided with a corresponding ledge 27 which engages the protruding part 25. Furthermore the fire screen is provided with a notch 28 which makes it possible, when the door is open, easily to lift the fire screen upwardly out of the dovetail guide. On the inner side of the door body 12 there is provided a horizontal inclined ledge 29 which protrudes into the planishing opening and is provided with feet 30 resting at the lower edge of the door frame 10. When the door is to be opened, first the square head bolt 24 is turned so that the latch 23 is released and turned out of its latching position in which it engaged the hooks 20 and 21. After the door body has now been turned outwardly by a certain angle around the hinge bolt 14, the free surface of the cut-out 17 engages the coupling

pin 18. If now the door body 12 is turned further, the coupling pin 18 will take along also the hinge bolt 14 and thus the hook 20. The closing operation of the door is effected in the reverse order. During the latching operation the latch slides over the slant surface 22 of the hooks 20 and 21 and thus presses the door body 12 parallel to itself against the door frame 10 whereby the sealing edge 4 and the sealing strip 5 evenly abut the sealing surface 11.

The embodiment shown in Figure 9 differs from the embodiments described above in that also the hook 20 is rigidly connected to the door frame 10 near the outer side of the hinge. While discarding the possibility of turning the hook 20, the entire structure is somewhat simplified. The arrangement of the ledge 29 supports the effect of the slant surface of the sealing strip 5 inasmuch as the tar condensate which deposits at the door is returned to the oven chamber over the slant surface of the ledge 29. This will make sure that the condensates will not escape toward the outside when the door is being opened.

According to a still further embodiment of the invention, the self-sealing arrangement may be effected by a sealing ledge arranged at the door frame and extending over the entire circumference thereof. When the closure body is in its closing position this sealing ledge contacts a corresponding sealing surface of the closure body. Such an arrangement is shown in Figs. 10 and 11 according to which the outside of the closure frame 6a is provided with a flange 2a extending all the way around. Flange 2a carries a plurality of even spaced threaded hook-shaped bolts 3a. These bolts in cooperation with nuts 8a hold a sealing ledge composed of a plurality of strips in yieldable and frictional engagement with the flange 2a. Inserted into the closure member 1a is a bolt 31a provided with thread and carrying the closure yoke or lever 32a. Bolt 31a is provided with a square head 33a. In order to close the planishing opening, the closure body 1a is lifted by its ear 34a and moved in front of the planishing opening in such a manner that the lever or yoke 32a firmly enters the hooks 35a carried by the closure frame 6a. When now the bolt 31a by actuation of the square head 33a is screwed out of the body 1a, the body is moved toward the closure frame as a result of which the sealing surface 7a of the closure body 1a is firmly pressed against the sealing ledge 4a arranged on the closure frame 6a. Inasmuch as the sealing ledge 4a is yieldably and frictionally clamped against flange 2a, it will be able to adapt itself similar to the embodiments described hereinbefore, to any unevenness of the sealing surface 7a which may be caused by warping.

50

It is, of course, understood that the present invention is, by no means, limited to the particular structural arrangements shown in the drawings, but also comprises any modifications within the scope of the appended claims.

5 What I claim is:

1. A closure arrangement for the planishing opening of horizontal coke oven chambers, which comprises in combination, a frame confining the planishing opening including sealing means, a closure member, sealing means mounted on said closure member and adapted when said closure member is placed into closing position for closing said planishing opening to contact the sealing means of said frame, at least one of said sealing means being metallic and one of said sealing means being frictionally held in its respective position, first guiding means connected to that side of said closure member which faces said frame, a fire screen provided with second guiding means slidably engaging said first guiding means to be slidably guided thereby, ledge means connected to the lower side of said closure member and extending below said fire screen so as to support the same, and locking means for pressing said first-mentioned sealing means and said second sealing means tightly against each other while locking said closure member to said frame.
- 10 2. An arrangement according to claim 1, in which the fire screen is provided with notch means on its inner side for engagement with means for sliding said fire screen out of said door body.
- 15 3. An arrangement according to claim 1, in which said 20 first guiding means is formed as a dovetail guide.
- 25 30
